CLAIM

The ornamental design for a wireless charger, as shown and described.

DESCRIPTION

FIG. 1 is a front, left, top perspective view of a wireless charger, showing my new design;

FIG. 2 is a rear, right, bottom perspective view thereof;

FIG. 3 is a rear, left, top perspective view of the enlarged scale thereof;

FIG. 4 is a front elevational view of the enlarged scale thereof;

FIG. 5 is a rear elevational view of the enlarged scale thereof;

FIG. 6 is a left side view of the enlarged scale thereof;

FIG. 7 is a right side view of the enlarged scale thereof;

FIG. 8 is a top plan view of the enlarged scale thereof;

FIG. 9 is a bottom plan view of the enlarged scale thereof;

FIG. 10 is an enlarged view of a portion of the wireless charger shown in detail 10 in FIG. 8;

FIG. 11 is an enlarged view of a portion of the wireless charger shown in detail 11 in FIG. 8; and,

FIG. 12 is a front, left, top perspective view of the wireless charger in an alternate configuration.

The dashed broken lines in the figures are for the purposes of illustrating portions of the wireless charger and form no part of the claimed design.

The dash-dot-dash broken lines encircling portions of the wireless charger in FIG. 8 and illustrated in enlarged views in FIGS. 10 and 11 form no part of the claimed design.

1 Claim, 12 Drawing Sheets
